UNITED STATES PATENT OFFICE

WILLIAM F. ZABRISKIE, OF DETROIT, MICHIGAN, ASSIGNOR TO GABRIEL STEEL COMPANY, OF DETROIT, MICHIGAN, A CORPORATION OF MICHIGAN

SECURING CLIP FOR METALLIC LATH

Application filed February 20, 1928. Serial No. 255,849.

The invention relates to a means for securing metallic lath or open mesh fabric to floor and ceiling joists and consists in the novel construction of a securing clip and in the 5 method of attaching the same as hereinafter set forth.

In the drawings:—

Figure 1 is a side elevation of the clip.

Figure 2 is an end elevation thereof.

10 Figure 3 is a plan view.

Figure 4 is a side elevation showing the manner of first engaging the clip with the metallic lath.

15 Figure 5 is a similar view after the clinching operation.

Figures 6 and 7 are perspective views of the clip engaging the fabric respectively before and after the clinching operation.

In the construction of reinforced concrete 20 floors and also in the construction of ceilings it is usual to employ a metallic lath which is arranged adjacent to the floor or ceiling joists. These joists are usually formed of metallic bars or structural shapes such as I-beams 25 channel beams, etc., and the lath is laid adjacent to either the upper or lower flange of such beams according to whether it is a floor or ceiling construction. It is necessary, however, to firmly attach the lath to the beams 30 which I accomplish in the following manner: A is a clip preferably formed of wire having a horizontal portion B and parallel prongs C, C' for insertion through the mesh of the latter. The prongs C are connected 35 to the horizontal portion B through the medium of loops D, D' projecting oppositely from the prongs and preferably at an oblique angle thereto as shown in Figures 1—3.

To attach the lath by such clips the prongs 40 C, C' are inserted through apertures in the lath so as to embrace the flange of the beam which as indicated in Figure 4 is an I-beam E. The workman then engages lever arms with the upwardly projecting loops D, D' 45 preferably pipe sections which may be sleeved over said loops and which therefore extend obliquely and crossing each other. When thus engaged the lever arms are moved outward into the position indicated in Figure 5 which bends the loops D, D' from an

inwardly extending oblique position to an outwardly extending oblique position. At the same time the prongs C, C' will be swung inward into the position shown in Figure 5 where they are clinched to the under side of 55 the flange of the beam.

The operation just described is used in floor construction where the metallic lath is laid on top of the beams. In ceiling construction the only difference is that the lath is arranged 60 on the under side of the beam but is secured in precisely the same manner.

While I have described my improved clip as formed of bent wire it is obvious that it might be constructed of any other suitable 65 material.

What I claim as my invention is:

1. A clip for securing an open mesh fabric to a supporting member comprising a body portion for lying adjacent to the fabric having 70 prongs at the opposite ends thereof for insertion through the mesh of the fabric to embrace the supporting member and portions intermediate said prongs and said body portion projecting on the opposite side of the 75 fabric and bendable relative to said body portion to carry said prongs into clinching position.

2. A clip for securing an open mesh fabric to a supporting member comprising a body portion for lying adjacent to the fabric, parallel prongs at the opposite ends of said body portion insertable through the mesh of the fabric to embrace the supporting member and portions intermediate said prongs and body 85 portion extending obliquely on the opposite side of the fabric and bendable relative to said body portion to carry said prong into clinching position.

3. A clip for securing an open mesh fabric 90 to a supporting member comprising a wire bent to form substantially parallel prong portions, return bent loops extending oppositely from said prongs and obliquely thereto and a central portion connecting said loops for 95 the purpose described.

4. A clip for securing an open mesh fabric to a supporting member comprising a portion bearing against the outer face of the fabric, a prong portion insertable through the fabric, 100

a portion also outside of said fabric integral with and intermediate said prong portion and first mentioned outer portion and bendable in relation to the latter to carry said prong into clinching engagement with said supporting member, and means for holding said outer portion from movement to disengage said clinched prong.

In testimony whereof I affix my signature.
